NAVIGATIONAL PLOTTING INSTRUMENT

Jack E. Pelletier, Jr., 364 1st St., Oakland, Calif.

Filed Aug. 3, 1964, Ser. No. 81,107

Term of patent 14 years

(Cl. D52—6)

FIG-1FIG-2

FIGURE 1 is a perspective view of a navigational plotting instrument showing my new design; and

FIGURE 2 is a side elevational view thereof.

The bottom of the instrument is flat and plain in appearance.

I claim:

The ornamental design for a navigational plotting instrument, substantially as shown and described.
